UNITED STATES PATENT OFFICE

2,510,664

HAIR TREATING APPARATUS

Robert W. Shield, Chicago, Ill.

Application December 14, 1945, Serial No. 634,976

7 Claims. (Cl. 132--9)

1

This invention relates to hair treating apparatus and more particularly to apparatus for drying hair while it is held in a desired configuration.

It has been proposed to dry hair by winding it on a hollow, perforated spindle or spool through which heated air is forced so that the air will circulate outwardly through the spool and the hair wound thereon. In such devices, the hair dries more rapidly opposite the perforations in the spindle than over the solid wall portions so that uniform drying is not obtained. It is also necessary to employ external holding devices, such as pins or clips, to hold the hair in place on the spindle.

It is one of the objects of the present invention to provide a hair treating apparatus in which the hair is dried uniformly and quickly. According to one important feature of the invention, air is circulated inwardly through hair held on a spindle so that all portions of the hair are subjected to substantially the same air flow.

Another object is to provide hair treating apparatus in which a clamp device serves both to hold hair on the spindle and to direct air through the hair.

Still another object is to provide hair treating apparatus including a clamp device which is so formed as to hold the hair and to direct air through it in the desired manner. Preferably, the clamp is so arranged as to direct a certain amount of air against the head of the user thoroughly to dry all portions of the hair.

A further object is to provide a spindle or spool for holding hair during drying, which is so constructed that all portions of the hair have substantially equal circulation of air therethrough.

The above and other objects and advantages of the invention will be more readily apparent from the following description when read in connection with the accompanying drawing, in which—

Figure 1 is a partial perspective view of a complete apparatus embodying the invention;

Figure 2 is a transverse section illustrating the apparatus in use during a hair drying operation;

Figure 3 is a central section through the clamp device looking toward one of the jaws; and

Figure 4 is an elevation of a spindle.

As shown in the drawings, the apparatus of the present invention includes a spindle or spool indicated generally at 10 on which hair may be wound so that it will be held in a desired configuration during drying. The spool or spindle may be formed of any desired material, such as metal or plastic, and is preferably shaped with

2

a minimum diameter at its central portion tapering to larger diameters at its ends. The spool body is formed with a series of axially extending ribs 11 which are preferably roughened at their outer edges to hold the hair against slipping thereon. To improve circulation of air through the hair during drying, the body is formed with a plurality of enlarged passages 12 extending therethrough between adjacent ribs and connected to the spaces between the remaining ribs by passages 13.

In using the spool, hair may be wound thereon by first starting the outer end of a strand of hair on the spool body and winding the hair on the spool until the spool lies adjacent the head of the user. The position of the hair on the spool is indicated generally at 14 in Figure 2.

When the hair is wound on the spool, as described, it is held in place thereon by a clamp device comprising a pair of hollow body members 15 which may be molded of plastic, or the like, and which are pivotally interconnected by an elongated pivot pin 16. The jaws may be urged resiliently together by a coil spring 17 carried by the pivot pin with its opposite ends engaging the jaws above the pivot, as seen in Figure 2, so that the lower operating portions of the jaws will tend to come together. To open the jaws, they may be provided with extending finger pieces 18 to be engaged by the fingers of an operator.

The inner walls of the jaws, as indicated at 19, are formed by relatively thin sheets or plates which may preferably be of metal and which are perforated substantially throughout their entire area. The inner sheets or plates 19 are connected at their lower ends to the outermost edges of the jaws and may be pivotally connected together by hinge portions 21 thereon which encircle the pivot pin 16.

Air or other drying fluid is supplied to the clamp device through a flexible tube 22 which may connect to a blower and heater unit. The tube 22 is expanded at its lower end and is preferably vulcanized or cemented to the jaws, as shown, so that air supplied thereby will circulate into the hollow jaws and out through the perforations in the sheets 19.

In using the clamp device, it is opened by squeezing the finger pieces 18 together so that the jaws can be passed around a spindle 10 and the mass of hair 14 wound thereon. When the finger pieces are released, the jaws will come together around the spindle and the hair, in the manner best shown in Figure 2, to hold the hair in place on the spindle. When air is forced through the

tubing 22, it will circulate through both of the hollow jaws and will flow out through the perforations in the inner sheets 19. This air which may be heated flows inwardly through the mass of hair wound on the spindle and may circulate out of the clamp axially through the spaces between the ribs 11 on the spindle. The passages 12 and 13 provide for free circulation of air through the spindle so that the hair will be uniformly and quickly dried. At the same time, a certain amount of air will flow out between the separated lower edges of the jaws to be directed toward the head of the user so that the hair immediately adjacent the head will also be dried. In this way the hair will be dried quickly while being held in a desired configuration on the spindle. It will be understood that in use a plurality of clamp devices and spindles might be used simultaneously on the head of a single user so that all of the hair can be dried in a minimum amount of time and with no discomfort.

While one embodiment of the invention has been shown and described in detail herein, it will be understood that it is illustrative only and is not intended as a definition of the scope of the invention, reference being had for this purpose to the appended claims.

What is claimed is:

1. Hair treating apparatus comprising a hair holding device adapted to hold hair to be treated, in a desired configuration, a clamp including a pair of hollow jaws perforated on their inner surfaces and means urging the jaws together to clamp a holding device and the hair held thereby, and means connected to the clamp to conduct air through the perforated inner surfaces of the jaws.

2. Hair treating apparatus comprising a hair holding device adapted to hold hair to be treated in a desired configuration, a clamp including a pair of arcuate pivotally connected hollow jaws having perforated inner surfaces, means urging the jaws together to clamp around a holding device and the hair held thereby, and means to conduct air to the clamp to flow through the perforated inner surfaces thereof.

3. Hair treating apparatus comprising an elongated spindle formed with axially extending ribs about which hair is adapted to be wound, an elongated clamp having hollow jaws to engage and substantially enclose the spindle and the hair wound thereon, the inner surfaces of the jaws being perforated, and means to conduct air to the clamp to flow through the inner perforated surfaces of the jaws and through the hair wound around the spindle.

4. Hair treating apparatus comprising an elongated spindle formed with axially extending ribs about which hair is adapted to be wound, an elongated clamp having elongated hollow jaws pivoted together and having cylindrical perforated inner walls, the jaws being adapted to engage a spindle and the hair wound thereon with the perforated inner walls lying against the hair, and means to conduct air to the clamp to flow through the perforated walls and through hair held thereby.

5. In hair treating apparatus, a clamp comprising a pair of hollow pivotally connected jaws, each of said jaws having a perforated substantially semi-cylindrical inner surface, a spring yieldingly urging the jaws together and a connection to the jaws to supply air to their interiors.

15 6. In hair treating apparatus, a clamp comprising a pair of hollow pivotally connected jaws, each of said jaws having a perforated substantially semi-cylindrical inner surface, a spring yieldingly urging the jaws together and a flexible conduit connected to the clamp to conduct air into the jaws to flow out through the perforated inner surfaces thereof.

20 7. In hair treating apparatus, a spindle comprising an elongated body formed with a series of axially extending ribs about which hair is adapted to be wound, the body having an axially extending opening therethrough and transverse passages connecting the opening with the spaces between the ribs, a clamp including a pair of hollow pivotally connected jaws, each having a perforated substantially semi-cylindrical surface 30 to engage and hold a spindle with hair wound thereon, and means to conduct air into the jaws to flow through the perforated inner surfaces and the hair and the passages and opening in the spindle.

25 ROBERT W. SHIELD.
